REFRIGERATING APPARATUS

Edmund F. Schwellen, Dayton, Ohio, assignor to
General Motors Corporation, Dayton, Ohio, a
corporation of Delaware

Application May 31, 1935, Serial No. 24,371

8 Claims. (Cl. 220—9)

This invention relates to refrigerating apparatus and more particularly to refrigerator cabinets.

Heretofore, refrigerator cabinets have largely been made by fastening metal panels upon wood frames. This construction, while it could be used to provide a satisfactory refrigerator cabinet, was unnecessarily heavy, complicated, difficult to manufacture, required considerable amounts of expensive hand labor and had numerous seams or spaces between the panels which were required to be sealed or closed. In such a cabinet, the outer wall could not be depended upon to seal the insulation.

It has recently been proposed to make the outer portion of the cabinet of a continuous sheet of metal which will not only form a continuous smooth exterior for the cabinet, but which will also serve the functions of a frame.

It is an object of my invention to provide a frameless sheet metal cabinet in which exposed sheet metal joints or welds are eliminated upon the exposed sides of the cabinet.

It is another object of my invention to provide a frameless sheet metal cabinet in which an improved sealing of the outer walls of the cabinet is provided to prevent external air from gaining access to the insulating space.

It is a further object of my invention to provide a frameless sheet metal cabinet construction which is easy to assemble and manufacture.

Further objects and advantages of the present invention will be apparent from the following description, reference being had to the accompanying drawings wherein a preferred form of the present invention is clearly shown.

In the drawings:

Fig. 1 is a vertical sectional view of a refrigerator cabinet embodying my invention;

Fig. 2 is a section along the lines 2—2 of Fig. 1;

Fig. 3 is a section along the lines 3—3 of Fig. 1; and

Fig. 4 is a sectional view similar to Fig. 1, but showing the cabinet in one of the early stages of assembly.

Referring now more particularly to the drawings, there is shown a refrigerator generally designated by the reference character 20 provided with outer sheet metal walls 22 which are formed by forming a flanged door opening 24 in a flat sheet of metal, and at the same time forming the ornamental panels 26 directly beneath the door opening. The lower edge of the sheet adjacent the panels 26 is provided with a flange 28 and the sheet is then bent on either side of the

door opening 24 to form the side walls of the cabinet and then bent near the opposite edges of the sheet as best shown in Fig. 2, and connected by a second sheet which extends across the back of the cabinet to form the rear walls. This second sheet is fastened to the edge portions of the sheet extending around the three walls by lock seams (not shown) which are formed upon a seaming machine in which the outer sheet metal portion extends over a fixture, and the lock seams are then hermetically sealed by applying asphalt or solder to the seam or by welding the seam. This rear sheet 30 stops short of the bottom of the cabinet as shown at 32 so as to provide an opening 33 in the rear portion of the bottom of the cabinet.

Heretofore, before completing the outer walls, it has been necessary to insert a partition wall which would separate the machinery compartment 34 from the food compartment 36 before the closing of the outer walls by the rear sheet on the lock seaming machine. In the support of this partition wall it was desired to avoid any spot welds upon the exposed surfaces of the front and sides of the cabinet. This made it necessary to remove the outer walls from the fixture within which they were held for the forming of the side walls in order to place the partition wall in place. After the partition wall was put in place, it was then necessary to again place the fixture within the outer wall structure 22 and take the assembly to the lock seaming machine which would lock seam the rear wall to the side walls. The presence of the partition wall made the lock seaming operation somewhat difficult and also required the extra handling incident to removing the fixture, inserting the partition wall, replacing the fixture and returning the assembly to the machine where the forming and lock seaming was to be done. Therefore, in my cabinet I have completed the outer walls first.

The presence of the flanged door opening 24 and the presence of the flange 28 at the bottom of the cabinet makes the problem of the insertion of the partition wall slightly complicated. I, however, have solved this in a simple manner by providing a partition wall 38 which is welded to a U-shaped piece 40 having a flange 42 at its upper edge which is spot welded to the edges of the partition wall 38. The edges of the partition wall 38 are beveled or chamfered as shown at 44 for a reason to be hereinafter explained. The member 40 extends downwardly from the edges of the partition wall on three sides and is provided with a doubled or bent-

over flange 46 at its lower edge. In order to insert this assembly into the cabinet, I have cut away at an angle the rear edge portions of the member 40 as shown at 48 so that this assembly 5 may be placed into the wall structure at the top in an angular position as shown in full lines in the figure and moved directly downwardly in that angular position until it reaches the lower portion of the assembly after which it is placed 10 in the position shown in dotted lines indicated by the reference character 50 and tilted into position in the bottom of the cabinet with the flange 46 resting upon the flange 28 as shown in Fig. 1. The cut away portion 48 permits the 15 swinging of the assembly into place with the edges of the partition wall 38 meeting the outer walls of the cabinet. If the portion 48 were not cut away, as shown in the figure, it would be impossible to put the partition wall in place 20 without opening or slitting the outer walls of the cabinet.

After this, the upper transverse partition 52 provided with flanged edges 54 which fit tightly against the top inner edges of the outer walls 22 25 is put in place. This top partition wall, likewise, has its edges beveled or chamfered in a manner somewhat similar to the partition wall 38 excepting that the partition wall 52 and its flanged portions are in one piece. The top partition wall 52 is provided with a central opening which at a later stage of the assembly is closed 30 by a rubber or metal grommet 56. This upper transverse partition is welded in place by spot welds and if desired the flange 46 of the lower 35 transverse partition assembly may be spot welded to the flange 28 at this time. The rear portion of the lower transverse partition is provided with a flange 49 at the rear edge which is spot welded to the lower edge of the rear sheet 30 at this 40 time. Otherwise, the tight fit within the outer walls may be depended upon to hold either or both of these partitions in place.

This assembly is then passed through cleaning baths and the central opening in the top partition wall 52 permits the air which might be trapped within the upper portion of the assembly 45 to escape freely. Likewise, there has also been holes 58 provided for permitting access of the cleaning fluid to and drainage from the space 50 behind the panels 26. After the cleaning of this assembly, suitable outer and inner finish coatings are placed thereon as desired. Paint, lacquer, enamel, varnish or porcelain may be applied to the outer walls of the cabinet in order 55 to provide a suitable finish. After the proper coatings have been applied, an asphalt seal 60 is provided as best shown in Fig. 3 by pouring hot asphalt into the V-shaped well extending around the edges of the upper and lower partitions 60 52 and 38. This well is formed between the beveled or chamfered portion of the partitions and the adjacent portion of the outer walls. By providing such a well, a sufficient volume of asphalt is received into the well to provide enough 65 heat so that the asphalt will flow freely into the crevices and cracks before the asphalt is chilled so as to provide a certain hermetic seal which will prevent any outside air from gaining access to the insulation space. The grommet 56 is also 70 inserted in place and sealed with asphalt at this time.

In the bottom of the cabinet on top of the flange 46, there is placed a U-shaped angle iron member 62 which is bolted to the flange by bolts 75 64 which extend not only through the angle iron

member 62 and the flange 46, but also through the flange 28 and through the flange of the legs 66 which perform the dual purpose of strengthening the corners at the lower edge of the cabinet as well as supporting the cabinet. It is not necessary for the U-shaped angle iron member 62 to extend entirely around the bottom of the cabinet since the flange 28, the flange 46 and the legs 66 are sufficient to properly support the cabinet except at the rear portion thereof, which is not as strong on account of the opening 33.

The cabinet door 68 is provided with a gasket seal 70 which when the door is in the closed position fits tightly against the outer face of the cabinet immediately surrounding the door opening so as to complete the sealing of the outer wall of the cabinet.

Within the cabinet, there is provided a door jamb frame 72 which may be a preformed wood frame, or which may be four separate pieces of wood inserted individually around the sides of the door opening held between the flange 24 of the door opening and the adjacent side walls on the sides of the door opening and the partition 25 walls at the top and bottom of the door opening. These four pieces may be further held by nails extending through the flange 24 of the door opening into the wood pieces. Insulating slabs 20 30 35 40 45 50 55 60 65 70 75 80 85 90 95 100 are then placed in position in the walls of the cabinet and thereafter the inner liner assembly including the inner liner 76 and the door molding 78 are placed in position within the cabinet. The door molding which is fastened to the inner liner is also fastened to the door jamb frame so as to provide a support for the inner liner independently of the slabs of insulation. In the final step, an ornamental top cover 80 is placed over the top of the cabinet and provided with flanges 82 which come over the joint between the partition wall 52 and the upper edge of the cabinet so as to conceal any spot welding marks. Inasmuch as the lower partition wall 38 is only fastened to the outer walls at the bottom flange 28 and immediately above the opening 33 at the rear of the cabinet as shown by the reference character 41, none of the welded portions of the cabinet is exposed, since the back of the cabinet is ordinarily placed against a wall which conceals the back of the cabinet.

Thus, by my improved construction a smooth outer finish surface of a cabinet extending around three sides of the cabinet and into the fourth side is formed by my improved construction without any hand finishing being required and without any exposed joints. A hermetically outer sealed wall structure is provided which protects the insulation from the infiltration of external air and moisture. The assembly of the cabinet is simple and the forming thereof is relatively inexpensive.

While the form of embodiment of the present invention as herein disclosed constitutes a preferred form, it is to be understood that other forms might be adopted, all coming within the scope of the claims which follow.

What is claimed is as follows:

1. A cabinet including vertical sheet metal walls extending around the cabinet, said sheet metal walls being provided with an inturned 70 flange at one edge thereof, a partition wall spaced from said inturned flange extending between the vertical sheet metal walls, said partition wall having means extending to and resting upon said inturned flange for supporting said partition 75

wall, said extending means being located within confines outlined by radii extending from one edge of the partition wall having a length equal to the distance from that edge to the directly opposite edge of said partition wall.

5. 2. A cabinet including vertical outer sheet metal walls extending around a space to be enclosed, said outer sheet metal walls having plane wall portions, one of said plane wall portions being open adjacent one of its extremities, a partition wall within the confines of said outer sheet metal walls located between said open portion and the more distant extremity of said walls, said partition wall being fastened to edge portions bordering said open portion of said one plane wall portion and said partition wall being provided with supporting means extending to and being fastened to the adjacent extremities of the said other vertical outer sheet metal walls, 20 said supporting means being located within confines outlined by radii extending from one edge of the partition wall and having a length equal to the distance from that edge to the directly opposite edge of said partition wall.

25. 3. A cabinet including vertical outer sheet metal walls extending around a space to be enclosed, said outer sheet metal walls having plane wall portions, one of said plane wall portions being open adjacent one of its extremities, a partition wall within the confines of said outer sheet metal walls located between said open portion and the more distant extremity of said walls, said partition wall being provided with supporting means extending to and being fastened to the adjacent extremities of said vertical outer sheet metal walls, said partition wall having edge portions formed to provide a continuous well in cooperation with the adjacent portion of the outer sheet metal walls, said well 30 extending around the edge of the partition wall, and a sealing compound within the continuous well for providing an air tight seal between the edges of said partition wall and the adjacent portions of the outer sheet metal walls.

40. 4. A cabinet including vertical outer sheet metal walls extending around a space to be enclosed, said sheet metal walls being provided with a door opening therein having its center point displaced in a vertical direction from the mid point between the upper and lower extremities of the outer walls, transverse sheet metal partition walls within said outer sheet metal walls spaced substantially an equal distance in opposite directions from the edges of 45 said door opening to provide an enclosed space between the sheet metal partition walls and a second space within said outer sheet metal walls adjacent one of said partition walls and the first mentioned enclosed space, one of said outer sheet metal walls having an open portion adjacent said second space, said partition wall adjacent said second space being fastened to marginal portions of said open portion of said one outer sheet metal wall and being provided with supporting 50 means separate from said outer sheet metal walls but extending to and being fastened to one of the extremities of said other outer sheet metal walls, said supporting means being located within confines outlined by radii extending from one edge of the partition wall and having a length equal to the distance from that edge to the directly opposite edge of said partition wall.

55. 5. A refrigerator cabinet comprising an inner liner forming a refrigerating compartment within said cabinet and having an access opening,

insulating material surrounding said inner liner, and means forming a supporting structure for the liner and insulating material and forming as well the outer finish walls for the cabinet, said means comprising a substantially tubular sheet metal structure having an opening in one side adapted to register with said compartment access opening, said tubular sheet metal structure having the wall portions extending from the refrigerating compartment to form a second compartment, a partition wall within the extending portions of said tubular sheet metal structure dividing said second compartment from the inner liner and insulation for the refrigerating compartment, said partition wall having 15 sheet metal supporting means along three of its sides, said sheet metal supporting means extending along the inside of the tubular sheet metal structure and being fastened on said three sides only to the extremities of the extending portion 20 of said tubular sheet metal structure and being located within confines outlined by radii extending from one edge of the partition wall and having a length equal to the distance from that edge to the directly opposite edge of said partition wall, the fourth side of said partition being fastened directly to said tubular sheet metal structure.

6. 6. A refrigerator cabinet comprising an inner liner forming a refrigerating compartment within said cabinet and having an access opening, insulating material surrounding said inner liner, and means forming a supporting structure for the liner and insulating material and forming as well the outer finish walls for the cabinet, said means comprising a substantially tubular sheet metal structure having an opening in one side adapted to register with said compartment access opening, said tubular sheet metal structure having the wall portions extending from the refrigerating compartment to form a second compartment, a partition wall within the extending portions of said tubular sheet metal structure dividing said second compartment from the inner liner and insulation for the refrigerating compartment, said partition wall having sheet metal supporting means along three of its sides, said sheet metal supporting means extending along the inside of the tubular sheet metal structure and being fastened on said three sides only to the 35 extremities of the extending portion of said tubular sheet metal structure, said sheet metal supporting means being located within confines outlined by radii extending from one edge of the partition wall and having a length equal to 40 the distance from that edge to the directly opposite edge of said partition wall, the fourth side of said partition thereof being fastened directly to said tubular sheet metal structure.

7. 7. A cabinet including an outer sheet metal tubular wall structure, a partition wall extending transversely across the interior of said tubular wall structure to divide the interior of said tubular wall structure into compartments, said partition wall having supporting means extending to one of the extremities of the tubular wall structure, said supporting means being located within confines outlined by radii extending from one edge of the partition wall and having a length equal to the distance from that edge to the directly opposite edge of said partition wall.

8. 8. A cabinet including an outer sheet metal tubular wall structure, a partition wall extending transversely across the interior of said tubular wall structure to divide the interior of said tu-

bular wall structure into compartments, said partition wall having supporting means extending to one of the extremities of the tubular wall structure, said supporting means being located within confines outlined by radii extending from one edge of the partition wall and having a length equal to the distance from that edge to the di-

rectly opposite edge of said partition wall, said tubular wall structure having four sides and said partition wall being generally rectangular in shape, said tubular wall structure being provided with an opening in one of its sides for one of the compartments.

EDMUND F. SCHWELLER.
